(57) **CLAIM**

The ornamental design for a cooler box, as shown and described.

DESCRIPTION

FIG. 1 is a front and top perspective view of a cooler box, shown with the top lid open condition, showing my new design;

FIG. 2 is a rear and bottom perspective view thereof, shown with the top lid open condition;

FIG. 3 is a front elevation view thereof, shown with the top lid open condition;

FIG. 4 is a rear elevation view thereof, shown with the top lid open condition;

FIG. 5 is a left side elevation view thereof, shown with the top lid open condition;

FIG. 6 is a right side elevation view thereof, shown with the top lid open condition;

FIG. 7 is a top plan view thereof, shown with the top lid open condition;

FIG. 8 is a bottom plan view thereof, shown with the top lid open condition;

FIG. 9 is a partially enlarged view thereof, shown with the top lid open condition, taken from FIG. 1;

FIG. 10 is a partially enlarged view thereof, shown with the top lid open condition, taken from FIG. 1;

FIG. 11 is a partially enlarged view thereof, shown with the top lid open condition, taken from FIG. 2;

FIG. 12 is a front and top perspective view thereof, shown with the top and main lid in closed condition; and,

FIG. 13 is a front and top perspective view thereof, shown with the main lid open condition.

The broken lines in the figures illustrate portions of the cooler box that form no part of the claimed design. The dash-dot broken lines in FIGS. 1, 2, 9, 10 and 11 represent boundaries of the partially enlarged views and form no part of the claimed design.

1 Claim, 13 Drawing Sheets
